(57) **CLAIM**

The ornamental design for a bowl, as shown and described.

DESCRIPTION

FIG. 1 is a front, top perspective view of a bowl showing one embodiment of our new design;

FIG. 2 is a front, bottom perspective view thereof;

FIG. 3 is a front view thereof, the rear view being a mirror image of the front view;

FIG. 4 is a right side view thereof, the left side view being a mirror image of the right side view;

FIG. 5 is a top view thereof; and

FIG. 6 is a bottom view thereof.

FIG. 7 is a front, top perspective view of the bowl of FIG. 1 showing the bowl with unclaimed subject matter in the form of a plate used as a cover;

FIG. 8 is a front, bottom perspective view thereof;

FIG. 9 is a front view thereof, the rear view being a mirror image of the front view;

FIG. 10 is a right side view thereof, the left side view being a mirror image of the right side view;

FIG. 11 is a top view thereof; and

FIG. 12 is a bottom view thereof.

FIG. 13 is a front, top perspective view of a bowl showing one embodiment of our new design;

FIG. 14 is a front, bottom perspective view thereof;

FIG. 15 is a front view thereof, the rear view being a mirror image of the front view;

FIG. 16 is a right side view thereof, the left side view being a mirror image of the right side view;

FIG. 17 is a top view thereof; and

FIG. 18 is a bottom view thereof.

FIG. 19 is a front, top perspective view of the bowl of FIG. 13 showing the bowl with unclaimed subject matter in the form of a plate used as a cover;

FIG. 20 is a front, bottom perspective view thereof;

FIG. 21 is a front view thereof, the rear view being a mirror image of the front view;

FIG. 22 is a right side view thereof, the left side view being a mirror image of the right side view;

FIG. 23 is a top view thereof; and,

FIG. 24 is a bottom view thereof. The features shown in broken lines depict environmental subject matter for use with the bowl that forms no part of the claimed design.
